Primary Examiner — Catherine A Tuttle(74) *Attorney, Agent, or Firm* — Kirton McConkie; Evan R. Witt(57) **CLAIM**

The ornamental design for a toy golf club caddy, as shown.

DESCRIPTION

FIG. 1 is a front perspective view of a toy golf club caddy showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The appearance within the unshaded central region of FIG. 7 forms no part of the claimed design.
